UNITED STATES PATENT OFFICE.

WALTER MACKERSIE SMITH, OF JESMOND, NEWCASTLE-UPON-TYNE, COUNTY OF NORTHUMBERLAND, ENGLAND.

RELIEF-VALVE FOR LOCOMOTIVES.

SPECIFICATION forming part of Letters Patent No. 425,265, dated April 8, 1890.

Original application filed July 3, 1889, Serial No. 316,477. Divided and this application filed September 3, 1889. Serial No. 322,817. (No model.) Patented in England January 11, 1889, No. 571; in France June 5, 1889, No. 198,750, and in Belgium June 5, 1889, No. 86,529.

To all whom it may concern:

Be it knownth at I, WALTER MACKERSIE SMITH, a subject of the Queen of Great Britain and Ireland, residing at Jesmond, Newcastle-upon-Tyne, in the county of Northumberland, England, have invented certain new and useful Improvements in Relief-Valves for Locomotive-Engines, (for which patents have been obtained in England, No. 571, dated 10 January 11, 1889; in France, No. 198,750, dated June 5, 1889, and in Belgium, No. 86,529, dated June 5, 1889,) of which the following is a specification.

This application is filed as a division of my 15 pending application for United States patent, filed July 3, 1889, Serial No. 316,477.

This invention has for its object improvements in locomotive-engines.

Balanced valves have been used for distributing steam in most classes of engines. In marine and other engines they always work under pressure of steam, whereas locomotive-engines when descending inclines have their momentum kept up by the action of gravity 20 and continue to move after steam has been shut off. Assuming balanced valves, including piston-valves, to be employed instead of the ordinary slide-valves, the action of these valves may be compared to what would occur assuming an ordinary slide-valve to be 25 used that could not rise or lift off the face; hence by the action of the engine-piston steam would be exhausted from the steam-pipe and steam-chest, and, the valve not being able to lift, no air could pass from the atmosphere into the steam-chest, except the 30 small quantity that would pass in at the end of each stroke, and which would be quickly drawn out again by the receding piston. In consequence the engine would be unnecessarily retarded. Air passing down the exhaust-pipe would press on the piston in the opposite 35 direction to that in which it might be moving, and this pressure not being nearly counterbalanced by that due to the rarefied air, pressing on the opposite side of the piston, there would result undue tension of the piston-rod and connections during the backward

stroke and undue compression during the forward stroke. Now, according to this invention, the foregoing disadvantages are obviated by admitting steam alone in an automatic manner to the steam chest or cylinder of a locomotive which is running with the steam shut off. To this end the steam is admitted 50 automatically to the steam-chest and thence to the cylinder by a suitable valve or valves opened or caused to open by the pressure of the atmosphere when the pressure within the steam chest or cylinder falls below that 55 of the atmosphere. The steam so admitted acts as would steam admitted in the usual way from the boiler, and thus serves to prevent rarefaction in the steam chest and cylinder, so that at least a pressure equivalent, or approximately so, to that of the atmosphere is exerted on both sides of the piston until the distributing-valve cuts off 60 communication with that part of the cylinder behind the receding piston, when the 65 inclosed steam will expand, decreasing in pressure. Toward the end of the stroke the space in the cylinder on the opposite side of the piston by the same means has its communication cut off from the exhaust, the 70 steam being then compressed and forming a cushion which arrests the movement of the piston, thereby obviating undue strain such as hereinabove referred to. A similar result 75 might be obtained by admitting steam direct to the cylinder without passing through the steam-chest, when the pressure of the fluid exerted on the back of the receding piston would vary little throughout the stroke. The steam is caused to be admitted in limited 80 quantities when the main supply of steam is shut off at the regulator. To this end a piston is employed, or its equivalent, subject on one side to the atmospheric pressure and on the other side to the pressure in the steam 85 chest or cylinder. This piston is arranged to operate a valve—it may be a check-valve or a piston-valve—which controls the connection between the steam chest or cylinder and the boiler. When the atmospheric pressure is 90 greater than the pressure in the steam chest 95

or cylinder, the piston is moved in one direction and opens this valve to admit the steam. As soon as the pressure in the steam chest or cylinder becomes greater than the atmospheric pressure the piston is moved in the opposite direction and the inlet of steam is cut off.

Referring to the annexed illustrative drawings, Figure 1 shows, partly in section and partly in elevation, so much of a locomotive-engine as is necessary to illustrate the application thereto of apparatus according to this invention for automatically admitting steam alone to the steam-chests of the cylinders. Fig. 2 shows in longitudinal vertical section, to an enlarged scale, one of the apparatus detached, the steam-valve and part of the air-actuated piston being shown in elevation. Fig. 3 is an end elevation of the apparatus. Fig. 4 is a transverse section on the line O P.

Referring to Fig. 1, 1 is one of the working-cylinders of the engine, and 2 the steam-chest of such cylinder.

3 are liners in the steam-chest. It is in these liners that the piston-valves 3^a work in the example shown.

4 are live-steam spaces.

5 is an exhaust-steam space.

6 6^a are steam-ports in the liner.

7 7 are cylinder-ports.

8 8 are exhaust-ports in the liner.

To each steam-chest 2 is fitted, as shown in Fig. 1, an apparatus of the kind shown in Figs. 2, 3, and 4. This apparatus comprises a piston 21, arranged to slide in a casing 22, the interior of which communicates by a branch pipe 23 with the steam-space 4 in the steam-chest 2. The piston 21 is subjected on its outer side (i. e., the surface that faces to the left in Fig. 2) to the pressure of the atmosphere and on its inner side (i. e., the surface that faces to the right in Fig. 2) is subjected to the same pressure that exists for the time being in the space 4 of the steam-chest. The piston 21 is formed with a shoulder at 24, that serves to limit its outward movement. It is also formed or provided with a spindle or stem 25, that slides in a tubular guide 26, which also serves to limit the inward movement of the piston.

27 is a removable bush, that admits of the piston 21 being easily removed or replaced.

28 is a steam-pipe in communication at one end with the boiler, and 29 is a steam-valve for controlling the flow of steam through the pipe 28 to the casing 22 and thence to the space 4 in the steam-chest. The steam-valve 29 has a seat at 30 and is provided with a stem 31. The arrangement is such that when the atmospheric pressure is greater than the pressure in the steam-chest the piston 21 will move inward and its stem 25, acting against the stem 31 of the steam-valve 29, will force this steam-valve from its seat and admit steam from the pipe 28 to the space 4 in the steam-chest. When the pressure in the space 4 in the steam-chest becomes greater than the at-

mospheric pressure, the piston 21 will move in the opposite direction, releasing the steam-valve 29, which will then be forced upon its seat and will cut off the supply of steam.

From the foregoing description it will be understood that although the main supply of steam may be cut off at the regulator the steam-pressure in the space 4 of the steam-chest can never be reduced below that of the external atmosphere for the time being. At each stroke of the working-piston of the engine steam will be drawn past the valve 29, the steam-space 4, and one of the ports 7 until the cut-off takes place. This steam will then be expanded through the remainder of the stroke until the exhaust-port opens, whereupon there will be a slight inrush of air from the exhaust-pipe 5^a. On the return-stroke of the working-piston of the engine the steam from the engine-cylinder 1 will be expelled through the port 7, the exhaust-space 5, and the exhaust-pipe 5^a until the port 7 is again closed, whereupon the remaining steam will be compressed, and this compressed steam will act as a cushion to the working-piston of the engine until the port 7 is again opened to the steam-space 4. The steam so admitted will act as a lubricant to the internal working parts.

The apparatus hereinbefore described automatically comes into operation after the main supply of steam has been cut off at the regulator and continues in operation until the engine comes to rest, effectually preventing the pressure in the steam chest or cylinder, or in each, if applied to more than one, falling appreciably below that of the external atmosphere. When the engine comes to rest, the air-actuated plunger and steam-valve will be automatically operated in the reverse direction by the pressure within the steam chest or cylinder, and the automatic admission of steam will thus be arrested.

This invention will enable a balance-valve to be used for the distribution of steam to the cylinders of a locomotive without unnecessary strain being put on the piston-rod and other parts of the engine.

Apparatus according to this invention may be used in connection with valves other than balanced valves—for instance, with valves placed on the tops of cylinders and which do not fall from the faces.

What I claim is—

1. Apparatus for automatically admitting steam alone to the steam-chest or to the cylinder of a locomotive-engine and comprising a casing 22, provided with an inlet branch for steam and adapted to be connected to a steam-pipe and an outlet branch adapted to be connected to and with its interior in communication with said steam chest or cylinder, a valve 29, with stem 31, for controlling said steam-inlet, and a piston 21, arranged to slide in said casing and provided with a stem 25, adapted to act against said valve-stem 31 and open said valve when moved in one direction, said

- piston being subject on one side to the pressure of steam in the casing and on the other side to the pressure of the external atmosphere, substantially as herein described.
- 5 2. The combination, with the cylinder 1 and steam-chest 2 of a locomotive-engine, of a piston distributing-valve 11, arranged to work in said steam-chest, an apparatus for automatically admitting steam alone to said steam-chest when the pressure therein falls below that of the external atmosphere, and an external steam-pipe 28, for connecting said apparatus to the locomotive-boiler, said apparatus comprising a casing 22, secured to said steam-chest and having an outlet 23 in communication therewith and a steam-inlet in communication with said pipe 28, a valve 29, with stem 31, for controlling said steam-inlet, and a piston 21, arranged to slide in said

casing and provided with a stem 25, capable 20 of acting against said stem 31 and opening said valve when moved in one direction, said piston being subject on one side to the pressure of steam in said casing and on the other side to the pressure of the external atmosphere and arranged to prevent the entrance 25 of air to said casing, substantially as herein described, for the purpose set forth.

In testimony whereof I have signed my name to this specification in the presence of 30 two subscribing witnesses.

WALTER MACKERSIE SMITH.
